UNITED STATES PATENT OFFICE

LEONARD H. WHEELER, OF CHICAGO, ILLINOIS, ASSIGNOR TO STEWART-WARNER CORPORATION, OF CHICAGO, ILLINOIS, A CORPORATION OF VIRGINIA

PUMPING MEANS FOR GASOLINE GAUGES

Refiled for abandoned application Serial No. 182,698, filed May 11, 1927. This application filed May 19, 1930. Serial No. 454,111.

This application is a continuation in part of my application Serial No. 38,946, filed June 22, 1925.

The purpose of this invention is to provide an improved construction of a depth-indicating device, particularly adapted for indicating the depth of gasoline in the main fuel tank carried by a motor vehicle, having an indicating element or gauge face mounted upon the forward part of the vehicle, and therefore at a considerable distance from the tank the depth of whose liquid contents is to be indicated. It consists in the elements and features of construction shown and described as indicated in the claims.

In the drawings:—

Figure 1 is a diagrammatic view representing a motor vehicle having the fuel tank equipped with a device embodying this invention and connected for operation of the pumping device with a vacuum chamber of a vacuum fuel feed tank, the figure being intended particularly to indicate the relative positions on the vehicle of the tank or fuel container and the depth gauge, and to trace the connection between the two and of each of them with the vacuum tank;

Figure 2 is a diagrammatic view consisting of a vertical section of the fuel container and pressure pipe leading therefrom to the gauge, a vertical section of one form of the pumping device connected to the pipe line from the container pressure pipe to the pressure gauge, and a vertical section of a conventional construction of the nature of a pressure gauge;

Figure 3 is a portion of the section shown in Figure 2 upon a larger scale;

Figure 4 is a section on the line 4—4 of Figure 2;

Figure 5 is a detail section similar to Figure 3 and indicated also by the line 5—5 on Figure 6 showing a detail modification;

Figure 6 is a plan view of the form shown in Figure 5;

Figure 7 is a sectional view in a plane corresponding to that of Figure 3 and indicated also at the line 7—7 on Figure 8, showing another modification which consists in duplicating the mercury trap and pressure connections;

Figure 8 is a top plan view on reduced scale of the form shown in Figure 7;

Figure 9 is a sectional side elevation of the form shown in Figure 7, the plane of the section and the direction of view being indicated by the line 9—9 on Figure 8.

In the construction shown in the drawings, referring first to the diagrammatic view of Figure 1, the engine to be supplied with the fuel is seen at A; the main fuel supply tank at the rear of the vehicle is seen at B, and D indicates the pressure gauge mounted at the dash, E being the familiar vacuum tank to which the fuel is lifted by suction of the engine from the low tank B, and which in the present invention has a vacuum chamber E¹ connected by the pipe C¹ with the pumping device indicated as to totality by the letter C.

The fuel pipe line leading from the main supply tank B to the vacuum tank E is indicated at 10. Mounted fixedly with respect to the tank B and depending therein, opening for intake in the tank at a point below the lowest liquid level to be indicated, is a pressure pipe 11 which extends out through the top of the tank and is connected by a pipe 12 with the pressure gauge D for communicating to the pressure-responsive element of the pressure gauge the pressure of the head of liquid in the tank B, which, having sealed the lower intake end of the pipe 11, tends to compress the air in that pipe more or less as the liquid head in the tank is greater or less, this pressure indicated by the pressure gauge being therefore a correct measure of the depth of the liquid in the tank, unless in any instance there be air leakage at any point in the pressure line between the tank and the pressure gauge or the equivalent of air leakage consisting in the absorption of air by the liquid.

The primary purpose of the present invention is to avoid error in the indication of the pressure gauge which might be caused by absorption or leakage of the air which is liable to occur.

The expedient for this purpose, stated generally, is intermittently, preferably somewhat frequently, introducing air into the conduit which extends between the pressure

100

gauge and the pressure pipe intake to an extent sufficient to momentarily cause discharge of air into the conduit which extends between the pressure gauge and the pressure pipe intake to an extent sufficient to momentarily cause discharge of air from said conduit out through the intake of the pipe 11, substituting fresh air forced in by the expelling means so that upon cessation of the pressure by which the air is thus expelled,—which pressure is relieved instantly upon the venting which occurs at the lower end of the pipe 11 from which the air bubbles through the liquid,—the head of liquid in the tank 15 will operate normally for causing the liquid to be forced up into the pressure pipe and produce compression of the fresh air in normal condition therein for transmitting pressure to the pressure-responsive element of the 20 pressure gauge which shall be truly indicative of the head of liquid in the tank.

In considering this action it will be borne in mind that the suction operative for drawing liquid out of the tank through the pipe 25 10 is also operative through the pipe 12, and that the air bubbling up through the liquid as stated replaces in the space above the liquid in the tank the liquid which is withdrawn by the suction through the pipe 10.

30 In carrying out this expedient for freshening or rectifying the pressure-transmitting air in the pipe 12 there is provided a pumping device adapted to be operated by the intermittent suction which is operative in the 35 vacuum chamber of the vacuum tank E. A simple form of this expedient is seen in the drawings consisting of a pump chamber 20, 20^a, having a piston 21, 21^a reciprocating therein and normally held at one limit of its 40 stroke in the chamber by a spring 22, the piston chamber having connection from the other end with the vacuum chamber E¹ of the vacuum tank E into the top of which the terminal nipple 23 of said piston chamber is 45 adapted to be screwed, as seen in Figure 2, with the obvious result that at the suction phase of the vacuum chamber the piston 21, 21^a is retracted against the resistance of the spring 22 and produces a suction inflow of air 50 through a port 29. The pump chamber comprises a larger diametered part 20 and a smaller diametered part 20^a and the piston comprises correspondingly a larger diametered part 21 and a smaller diametered part 55 21^a at the inner end of the larger part—that is, the end toward which the piston is thrust and yieldingly held by the spring 22 at the normal position of the parts. The larger and smaller portions of the piston 21, 21^a 60 correspond in diameter to the larger and smaller portions 20, 20^a, of the piston chamber; and the atmospheric inlet port 29 opens into the piston chamber at the inner end of the larger portion, that is so that the farther 65 margin of the port is substantially at the

plane of the entrance to the reduced portion of the piston chamber, as most clearly seen in Figure 3. The port is designed to be of sufficient diameter to permit the larger portion of the piston to be thrust in by the spring 22 70 without any substantial resistance or impediment by reason of the necessity for driving out air through the port, from which it results that the retraction of the piston by the suction in the suction phase of the vacuum 75 tank is not materially impeded by the resistance to the inflow of air through said relatively free port.

Located laterally with respect to the pump barrel or piston chamber 20, 20^a, and communicating at the upper end therewith as hereinafter described, is a chamber 30. A duct 24 extending transversely in the upper part of the casting, F, in which the pump barrel or piston chamber is formed, leads from 80 the piston chamber and communicates downwardly with the upper end of a vertical bore in a lateral boss F¹ of the casting F, into which a pipe member 40 which contains the chamber 30 is drive-fitted, having apertures 85 as seen at 40^m, 40^m, for registering with the pipe members, 12, 12, respectively, and an exterior annular groove, 40ⁿ, at the zone of said apertures, 40^m, for maintaining communication between them. Said pipe member has its upper end closed by a bushing 41 whose central aperture registers with the downwardly open end 24^a of the duct 24, and having secured liquid-tight in it for extending downwardly at the center of the chamber 90 30, a depending pipe 25 which terminates at its lower end open at a short distance above the closed lower end of the pipe member 40, so that the air passage from the inlet port, 29, to the ports, 40^m, 40^m, which lead respectively 95 to the gauge, D, and to the fuel container, B, comprises a downwardly extending part in the pipe, 25, and an upwardly extending part in the annular space in the pipe, 40, around the pipe, 25, which affords a trap for liquid, 100 serving a purpose hereinafter indicated. The smaller part 21^a of the piston has an axially extended bore 27 which stops short at the plane of enlargement of the piston and at 105 that point communicates with a radial bore 115 28 which opens at the surface of the smaller part of the piston immediately above the shoulder between the two differently diametered parts of the piston. This bore 27 is counterbored at the upper end as seen at 27^a 120 to accommodate and form an upwardly facing seat 27^b for a ball check valve 26. The lower part of the chamber 30 within which the tube 25 terminates openly is utilized for containing a quantity of mercury indicated 125 at 42, which seals the lower end of the pipe 25 against the passage of air while it transmits pressure between the cavity of the pipe 25 and the annular cavity which constitutes the chamber 30. The lateral boss F is formed 130

- at its upper end as a T-fitting F², adapting the entire pump device to be interposed in the pipe line 12 which, as above described, leads to the pressure gauge, the section of 5 said pipe 12 leading from the tank B being connected to one end of the cross-arm of the T, and the other section, leading to the pressure gauge, being connected to the other end of said cross-arm.
- 10 Upon considering the operation of this construction it may be understood that at the suction phase of the vacuum tank the piston 21, 21^a will be retracted against the resistance of the spring 22, taking in air through the port 15 29 into the larger part 20 of the piston chamber, from which it passes by the duct 27 up past the check valve 26 into the counterbore 27^a in response to the partial vacuum which is created by the withdrawal of the smaller part 20 of the piston in the corresponding part of the piston chamber and in the duct 24 and pipe 25. Upon the return stroke of the piston under the reaction of the spring 22, occurring 25 when the suction phase of the vacuum tank ends and the atmospheric pressure is admitted to the tank, the air which has thus passed the check valve 26 and occupied the passages there-beyond down to the mercury, which is trapped in the lower part of the pipe member 30 40 and which seals the lower end of the pipe 25, is sufficiently compressed to drive the mercury down to the end of the pipe 25 and up in the chamber 30 around that pipe, permitting the air to bubble up past the lower end of 35 the pipe 25 and pass up into the chamber 30 to the entrance of the pipe members 12, 12, thus transmitting the pressure produced by the piston under the reaction of the spring 22 equally to the pressure gauge and to the main 40 fuel tank, restoring the status as to pressure in the pipe 11 and the pipe section 12 therefrom which may have been measurably lost by air leakage or absorption of air by leakage.
- In order to insure against the mercury escaping either back through the duct 27 and becoming trapped above the check valve 26 or being forced or flowing on through the chamber 30 into the pipe 12, as might possibly occur from the sudden reaction of the spring 45 50 55 60 65 70 75 80 85 90 95 100 105 110 115 120 125 130 22 giving it impetus, but more especially to insure against such escape of the mercury in case of tilting or inverting the apparatus in handling for mounting or demounting or being overturned in case of accident to the car, there is desirably inserted in the pipe 25 a felt plug 50, and in the annular space of the chamber 30 about the pipe 25 at the upper part of said space there is inserted a similar annular felt plug 51, those felt plugs being so porous as not to materially impede the passage of the air but adapted to effectually prevent passage of the mercury by either of the courses indicated.
- In Figures 5 and 6 there is shown a detail 65 modification of the construction, in which, instead of the pipe 25 extending axially within the chamber 30, a duct 25^a is bored in the casting F obliquely from the upper end of the piston chamber down toward the left, opening in the lower part of the chamber 30^a, 70 which corresponds to the chamber 30 of the previously described form, said chamber 30^a being formed directly in the boss F¹⁰ corresponding to F¹ of the previous form. In this modification, instead of giving the upper end 75 of the casting F the form of a T-fitting for connection with the pipe members 12, a T-fitting 60 is screwed into the upper end of the boss F¹⁰ for connection through its stem with the upper end of the chamber 30 in which a 80 felt plug 51^a, corresponding in function to the plug 51, is interposed and the pipes, 12, 12 are connected to the opposite ends of the cross-arm of the T as seen in Figure 6.
- In Figures 7, 8 and 9 there is shown a modification which involves duplicating the mercury trap, that is, forming two such straps, one upon each side of the pumping chamber, said traps having connections at their opposite sides for interposing them in pipes 12^x 90 and 12^y respectively which each connect a liquid reservoir whose contents are to be indicated with a gauge for indicating the same, said reservoirs being separate and independent and the gauges likewise being separate 100 and independent, as for example the fuel tank and the lubricant reservoir in the crank case of the engine served. It is not considered necessary to show these separate reservoirs or the respective gauges in the drawings, the same being indicated by name at the broken ends of the pipe connections shown in Figures 8 and 9 and with indications as leading to said reservoirs and gauges respectively.
- In this modification the parts and detail 105 features which are identical with the form shown in Figure 3, are indicated by the same reference characters, but the construction differs from that shown in Figure 3 to the extent that the lateral bosses in which the chamber for the pipe member 40 is formed are bored from the upper end for receiving this chamber, instead of from the lower end as in Figure 3, and are counterbored from the upper end to form a shoulder 70 for stopping 110 the upper end of the pipe member 40, which is flanged at the upper end for that purpose as seen at 40^x, the bushing 41 which carries the pipe 25 being correspondingly flanged as seen at 41^x in Figure 7; and a plug 80 is 115 screwed into the upper counter-bored end of the boss, clamping the flanges of the pipe 40 and bushing 41 upon said shoulder, as seen in Figure 7. In view of this detail construction for securing the pipe member 40 in the casting, the plug 80 is axially bored at 80^a and radially bored at 80^b for clearing the passage, which would otherwise be obstructed by the plug, from the upper end of the pump chamber to the pipe 25; and to 120 125 130

insure such communication in view of the plug being screwed into place for clamping the flanges as mentioned, the plug has a peripheral groove 80° for registering with the passage 24 at the screwed-in position of the plug.

I claim:—

1. An air pumping device for the purpose indicated consisting of a body having a cavity adapted for connection with a source of intermittent suction; a movable member for expanding and reducing the cavity; means yieldingly holding said member against movement in response to the suction through said connection, said body having an outlet from the cavity adapted for connection to transmit air pressure from the pumping device, and having an air inlet to the cavity positioned for admitting air thereto at the opposite side of the movable element from the suction connection, the passage from said air inlet to the outlet comprising a descending part succeeded by an ascending part forming a trap for liquid interposed in the line of pressure communicated from the pump to the outlet, and an air-permeable obstruction interposed between the trap and the outlet, and liquid occupying the trap to which said obstruction is impermeable.
2. The construction defined in claim 1, having an air-permeable obstruction anterior as well as subsequent to the trap.
3. An air pumping device for the purpose indicated consisting of a body having a cavity adapted for connection with a source of intermittent suction; a movable member for expanding and reducing the cavity; means yieldingly holding said member against movement in response to the suction through said connection, said body having a plurality of outlets from the cavity adapted for connection to transmit air pressure from the pumping device, and having an air inlet to the cavity positioned for admitting air to the cavity at the opposite side of the movable element from the suction connection, a liquid trap interposed between the pumping device and each of said outlets, said outlets being adapted for interposing the device in entirety in an air pressure line for delivering air from the pumping device in both directions in said line.
4. An air pumping device for the purpose indicated consisting of a body having a cavity adapted for connection with a source of intermittent suction; a movable member for expanding and reducing the cavity; means yieldingly holding said member against movement in response to the suction through said connection, said body having an outlet from the cavity adapted for connection to transmit air pressure from the pumping device, and having an air inlet to the cavity positioned for admitting air thereto at the opposite side of the movable element from

the suction connection, the passage from said air inlet to the outlet, comprising a liquid trap interposed in the line of pressure communicated from the pump to the outlet, said trap having its descending and ascending part respectively formed by interior and exterior tubular members of which the exterior member has a closed bottom, and a bushing at the top of said exterior member through which the interior member is sealed.

In testimony whereof, I have hereunto set my hand at Chicago, Illinois, this 17th day of May, 1930.
